UNITED STATES PATENT OFFICE

WILHELM B. BRONANDER, OF MONTCLAIR, NEW JERSEY

FIRE-EXTINGUISHER SUPPORT

Application filed March 31, 1928. Serial No. 266,161.

This invention relates to fire extinguisher supports.

The invention relates more particularly to the grenade type of fire extinguisher and to supports therefor.

The invention has for its salient object to provide a support so constructed and arranged that a plurality of grenades can be supported and will be automatically released in case of fire and, furthermore, so arranged that the grenades can be obtained for manual manipulation if desired.

Further objects of the invention will appear from the following specification taken in connection with the drawings, which form a part of this application, and in which

Fig. 1 is an elevational view of a support constructed in accordance with the invention;

Fig. 2 is a sectional elevation taken substantially on line 2—2 of Fig. 1, looking in the direction of the arrows;

Fig. 3 is a sectional elevation taken substantially on line 3—3 of Fig. 1, looking in the direction of the arrows; and

Fig. 4 is a horizontal sectional elevation taken substantially on line 4—4 of Fig. 1, looking in the direction of the arrows.

The invention briefly described consists of a support for grenade extinguishers comprising a shelf for supporting the grenades, the shelf being in turn supported by heat responsive means in such a manner that in case of fire the shelf will drop, releasing the grenades which will then fall and break, freeing the fire extinguishing fluid. The shelf is preferably supported in a glass cabinet through which an inspector or observer can ascertain whether the cabinet is properly supplied with grenades. Also, in case the fire occurs when someone is present, the cabinet can be broken and the grenades grasped and thrown at the fire.

Further details of the invention will appear from the following description.

In the particular form of the invention illustrated there is shown a cabinet having a back plate 10, preferably formed of metal, and having upwardly extending apertured tabs 11 for securing the cabinet to the wall.

The cabinet also has a top plate 12 of glass or suitable transparent material, and a front plate 13 and end plates 14 and 15 formed of like material.

The top, front and ends of the cabinet are supported in suitable channeled metallic guides or supports 20, 21, 22, 23, 24 and 25, as illustrated in the drawings, although the form of these supports may be varied if desired.

The grenades 26, four of which are shown, are supported in openings 30 formed in a shelf 31 carried by a base plate 32 having pivot lugs 33 at one end supported in U-shaped supporting brackets 34 carried by the angular supports 23 and 25 at one end of the cabinet.

The other end of the base plate and shelf are supported by a spring catch or latch 35 mounted in the other end of the cabinet. The spring catch has a hook shaped lower end 36 that engages a fusible pin 37 carried by lugs 38 which in turn are carried by a sloping end 39 of the shelf.

The fire extinguishing containers or grenades 26 are placed in position on the shelf and a fusible pin 37 is placed in position on the lugs 38. The shelf is then swung upwardly into the cabinet and the spring catch will snap over the pin 37 and will retain the shelf and grenades in the cabinet.

It will be noted that the right hand end of the base plate 32 extends beneath the lower end of the catch, thus preventing manual release of the catch.

The grenade support above described is particularly adapted for apartment houses and in case of a fire if no one is present the fusible pin will melt and release the shelf, which will swing down on its pivot lugs 33 and the grenades will drop to the floor and break, freeing the fire extinguishing fluid.

In order to facilitate the breaking of the cabinet to give access to the grenades, a hammer 40 is supported on a chain 41 carried by a lug 42 which in turn is formed on or secured to the frame of the cabinet.

If the fire occurs when someone is present, the front of the cabinet, or, if desired, the top, can be broken by the hammer or in any other

suitable manner, thus giving free access to the grenades which can then be thrown at the fire.

After the shelf has been automatically released by the melting of the pin 37 and the grenades or containers have been released, it is necessary only to replenish the shelf with containers and place a new fusible pin in position and then the shelf can be swung into the cabinet and will be retained therein by the spring catch.

Furthermore, as above stated, a glance at the cabinet will suffice to enable an observer to tell whether the cabinet is supplied with grenades.

By the term "grenade" as used in the specification and claims is meant a frangible container having a fire extinguishing fluid therein.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A support for grenade fire extinguishers comprising a cabinet, a shelf therein for releasably supporting a plurality of grenades, and movable to release the grenades from said cabinet and means including heat controlled means for releasably supporting said shelf in grenade supporting position.
2. A support for grenade fire extinguishers comprising a cabinet having a wall of transparent material, a shelf therein for releasably supporting a plurality of grenades, and movable to release the grenades from said cabinet and means including heat controlled means for releasably supporting said shelf in grenade supporting position.
3. A support for grenade fire extinguishers comprising a cabinet having an open bottom, a shelf therein for releasably supporting a plurality of grenades, and movable through said open bottom to release the grenades from said cabinet and means including heat controlled means for releasably supporting said shelf in grenade supporting position.
4. A grenade support comprising a cabinet having an open bottom, a shelf constructed to releasably support a plurality of grenades and pivoted in said cabinet, and adapted to swing downwardly through said open bottom, thereby to release the grenades from the cabinet and means including heat controlled means for releasably holding said shelf against swinging on its pivot and in grenade supporting position.
5. A grenade support comprising a cabinet having an open bottom, a shelf having an opening adapted to releasably receive a

portion of a grenade thereby to support the grenade, said shelf being pivoted in said cabinet and mounted to swing downwardly through said open bottom to grenade releasing position, and means including heat controlled means for releasably holding said shelf against swinging on its pivot and in grenade supporting position.

6. A grenade supporting cabinet having walls of transparent frangible material and having an open bottom, a shelf pivoted at one end in said cabinet and adapted to swing downwardly on its pivot through said bottom to grenade releasing position, said shelf having a plurality of openings adapted to releasably receive portions of a plurality of grenades whereby the shelf will engage and support the grenades from below, and means including heat controlled means for releasably holding the shelf against movement on its pivot and in grenade supporting position.

7. A support for fire extinguisher containers comprising a cabinet, a shelf pivoted in the cabinet for releasably supporting a fire extinguisher container, said shelf being adapted to swing downwardly out of the cabinet, to container releasing position a spring catch mounted in the cabinet for supporting the shelf, and fusible means carried by the shelf and releasably engaged by the spring catch.

8. A support for fire extinguisher containers comprising a cabinet, a shelf pivoted in the cabinet for releasably supporting a fire extinguisher container, said shelf being adapted to swing downwardly out of the cabinet to container releasing position, means in said cabinet for releasably holding the shelf against downward movement relative thereto, and fusible means carried by the shelf and engageable by said holding means.

9. A support for fire extinguisher containers comprising a supporting member, an element movably carried thereby and adapted to engage and support a fire extinguisher container when in one position, and to release said container when in another position, a fusible member on said element, and a catch on said supporting member engaging said fusible member and releasably retaining said element against movement relative thereto in grenade supporting position.

10. A support for fire extinguisher containers comprising a supporting member, an element movably carried thereby and adapted to engage and support a fire extinguisher container when in one position, and to release said container when in another position, a fusible member on said element, and a spring catch on said supporting member engaging said fusible member and releasably retaining said element against movement relative thereto in grenade supporting position.

11. A holder for fire extinguisher contain-

ers comprising a support, a shelf pivoted thereon and adapted to support a container when in one position, and to release said container when in another position, and means including a catch carried by the support and a fusible member carried by the shelf for releasably supporting the shelf in grenade supporting position.

12. A holder for fire extinguisher containers comprising a support, a shelf pivoted thereon and adapted to support a container when in one position, and to release said container when in another position, and means including a spring catch carried by the support and a fusible member carried by the shelf for releasably supporting the shelf in grenade supporting position.

13. A holder for fire extinguisher containers comprising a support, a member pivoted thereon and adapted to support a container when in one position, and to release said container when in another position, and means including a catch carried by the support and a fusible element carried by the member for releasably supporting the member in grenade supporting position.

14. A holder for fire extinguisher containers comprising a support, means carried thereby for releasably supporting a container, movable relative thereto to container releasing position, a fusible element carried by said means, and a resilient catch carried by said support and adapted to snap over said element and to releasably retain the container supporting means against movement relative to the support and in container supporting position.

15. A holder for fire extinguisher containers comprising a support, means pivoted thereto for releasably supporting a container, a fusible element carried by said means, and a resilient catch carried by said support and adapted to snap over said element and to releasably retain the container supporting means against movement to container releasing position.

16. A holder for fire extinguisher containers comprising a cabinet having an open bottom, a shelf therein for releasably holding the container, said shelf being movable downwardly through the open bottom of the cabinet to container releasing position, a plate connected to and movable with the shelf, said plate being disposed below the shelf and substantially closing the bottom of the cabinet, and means including a fusible element for releasably supporting the shelf in the cabinet in container supporting position.

17. A holder for fire extinguisher containers comprising a cabinet having an open bottom, a shelf therein for releasably holding the container, said shelf being movable downwardly through the open bottom of the cabinet to container releasing position, a plate connected to and movable with the shelf, said

plate being disposed below the shelf substantially closing the bottom of the cabinet, and means including a fusible element and a spring catch in the cabinet for releasably supporting the shelf in the cabinet in container supporting position.

18. A holder for fire extinguisher containers comprising a cabinet having an open bottom, a shelf therein for releasably holding the container, said shelf being movable downwardly through the open bottom of the cabinet to container releasing position, a plate connected to and movable with the shelf, said plate being disposed below the shelf and substantially closing the bottom of the cabinet, and means including a fusible element carried by the shelf and a spring catch mounted in the cabinet and engageable with said element for releasably supporting the shelf in the cabinet in container supporting position.

19. A holder for fire extinguisher containers comprising a support, a shelf pivoted thereon and adapted to releasably support a container, and means including a spring catch and a heat controlled element for releasably supporting said shelf against movement to container releasing position.

20. A holder for fire extinguisher containers comprising a support, a shelf pivoted thereon and adapted to releasably support a container, and means including a spring catch and a heat controlled element engageable therewith for releasably supporting said shelf against movement to container releasing position.

In witness whereof, I have hereunto set my hand this 3rd day of March, 1928.

WILHELM B. BRONANDER.
